G. CARPENTER

FUSE MOUNTING

Filed Sept. 2, 1927

UNITED STATES PATENT OFFICE.

GRANT CARPENTER, OF NEWARK, NEW JERSEY, ASSIGNOR TO WESTON ELECTRICAL INSTRUMENT CORPORATION, OF NEWARK, NEW JERSEY, A CORPORATION OF NEW JERSEY.

FUSE MOUNTING.

Application filed September 2, 1927. Serial No. 217,148.

This invention relates to a fuse mounting, and particularly to a fuse mounting for use with cartridge fuses.

An object of the invention is to provide a fuse mounting which serves as a housing for the enclosure of a cartridge fuse. A further object is to provide a mounting which may be used in an exposed position, such as upon a panel-board or an instrument case and which protects the fuse from damage and from inadvertent contact with wires or other conductors. More particularly an object of the invention is to provide a small mounting for miniature cartridge fuses, such as are employed in connection with measuring instruments, radio receivers, laboratory test panels and the like.

These and other objects of the invention will be apparent from the following specification when taken with the accompanying drawing, in which—

Fig. 1 is a central section through a fuse mounting which forms one embodiment of the invention, and

Figs. 2 and 3 are end and side elevations, respectively, of a cartridge fuse of the type adapted for use with the mounting shown in Fig. 1.

In the drawings the reference numeral 30 1 indicates a metal sleeve which has an outer flanged head 2 and an inner threaded portion 3 for receiving a nut 4 to mount the sleeve in an aperture in an insulating panel 5. The sleeve 1 serves as one terminal of the fuse mounting and, as shown in the drawing, the electrical connection thereto may be made by the terminal or strip 6 which is clamped between the nut 4 and the panel 5.

The second terminal of the mounting is 40 provided by the post 7 which passes through the sleeve 1 and projects beyond both ends thereof. The post 7 is secured to the sleeve 1 by bushings of insulating material 8, 9; the surfaces of the terminals which are engaged 45 by the bushing 8 being preferably roughened as at 10 to secure a rigid assembly of the parts. The post 7 is provided at a lower or inner end with a threaded extension 11 and nut 12 for securing the conductor 13 to the post. The bushing 9 is secured to the post 50 7 by molding the same upon the threads of the threaded extension 11, or by threading it upon the same. The other end of the post 7 projects beyond the flanged head 2 of the

sleeve 1 and is threaded to receive the 55 threaded insert 14 of an insulating cap 15. The cap 15 is provided with a depending flange 16 which forms a housing or chamber for the reception of a cartridge fuse.

The cartridge fuse for which this mounting is designed is longitudinally apertured to permit the same to slide over the extended portion of post 7 and rest upon the flanged head 2 of the sleeve. As shown in the drawings, the fuse consists of a tube 17 of insulating material having metallic caps 18 secured at the opposite ends thereof by indenting the metal at spaced points 19. The tube 17 is provided with a slot 20 for receiving the fuse wire 21, the end caps 18 70 being pressed into slot 20 to bring the ends of the fuse wire 21 inside the end surfaces of the cartridge fuse.

To prevent short-circuiting of the fuse on the stem 7, the inner edges of caps 18 fall 75 short of the bore through the tube 17, but they do extend inwardly far enough for the upper cap 18 to engage the metallic insert 14 in the cap 15.

To inspect or renew a fuse, the cap 15 80 is unscrewed from the stem 7, and the fuse may then be removed if it is found to be defective. The cap 15 retains the cartridge fuse firmly upon the seat formed by the outer end of the sleeve 1, and the depending 85 flange 16 protects the fuse from damage.

Although the invention is not limited to the construction of fuse mountings of any particular size, it provides a simple and attractive fuse mounting of small size which 90 is well adapted for use on instrument and radio panels. Mountings for use with miniature cartridge fuses may be so designed as to present an external appearance substantially identical with that of the binding 95 posts and terminal caps which are used on the instrument panel.

It is to be understood that the invention is not limited to the specific embodiment which has been illustrated and described 100 herein as various changes may be made in the several parts, their relative size, shape and location without departure from the spirit of my invention as set forth in the following claims.

I claim:

1. A fuse mounting comprising a sleeve member, a post member coaxial therewith,

an insulating bushing between said members for securing the same to each other, one of said members having an end face providing a seat for one end of a fuse and the second 5 of said members having a portion projecting beyond said seat, and means detachably secured to the said projecting portion of said second member for maintaining the fuse on said seat, said means including a 10 conducting element for electrically connecting the other end of the fuse and said second member.

2. A fuse mounting for a longitudinally apertured cartridge fuse comprising a tubular element having one end shaped to provide a seat for one end of a fuse, a post within and insulated from said element and having an end passing through and projecting beyond a fuse located on said seat end 20 of said element, and a cap secured to the end of said post to maintain said fuse on said seat, said cap including means for electrically connecting the other end of said fuse to said post.

25 3. A fuse mounting as set forth in claim 2 wherein said cap is provided with a depending flange for enclosing said fuse.

4. A fuse mounting for a longitudinally apertured fuse comprising a sleeve adapted 30 to extend through an aperture in a panel, said sleeve having an end portion at the face of the panel to provide a seat for one end of a fuse, a post passing through and

insulated from said sleeve, said post having a portion passing through and projecting 35 beyond a fuse located on said seat, a cap on said projecting portion of said post for clamping said fuse on said seat, said cap being formed of insulating material having a metallic insert therein for contacting with 40 the other end of said fuse and with said post, and means at the respective inner ends of said sleeve and post for making circuit connections thereto.

5. A fuse mounting as set forth in claim 45 4, wherein said cap is provided with a depending flange of insulating material for enclosing said fuse.

6. A fuse mounting comprising a sleeve 50 having a flanged outer end providing a seat for a longitudinally apertured cartridge and an inner end threaded to receive a nut for clamping said sleeve to a panel, a post coaxial with said sleeve and secured thereto and insulated therefrom, the outer end of 55 said post projecting beyond said seat portion of said sleeve and adapted to pass through a fuse seated thereon, and a metal bushing threaded upon said post to clamp a fuse between the same and said seat portion of said sleeve, said bushing contacting with the outer end terminal of the fuse.

In testimony whereof, I affix my signature.

GRANT CARPENTER.
